M. FALÓS

TOOL HANDLE

Filed Jan. 18, 1923

UNITED STATES PATENT OFFICE.

MICHAEL FALOS, OF BOSTON, MASSACHUSETTS.

TOOL HANDLE.

Application filed January 18, 1923. Serial No. 613,385.

To all whom it may concern:

Be it known that I, MICHAEL FALOS, a citizen of Ukraine, residing at Boston, in the county of Suffolk and State of Massachusetts, have invented certain new and useful Improvements in Tool Handles, of which the following is a specification.

This invention relates to new and useful improvements in tool handles of a type 10 adapted to operatively support cutting tools.

An important object of the invention is to provide a tool handle frame adapted for adjustment to accommodate tools of different lengths.

A further object of the invention is to construct a tool handle which embodies suitable construction to enable different types of tools to be supported thereby and to be 20 used to the advantage and comfort of the person operating the same.

A further object of the invention is to provide a tool handle that is simple in construction, cheaply manufactured, strong, 25 and durable.

Other objects and advantages of the invention will be apparent during the course of the following description.

In the accompanying drawings forming a 30 part of this specification and in which like numerals are employed to designate like parts throughout the same,

Figure 1 is a side elevational view of the tool handle embodying this invention and 35 wherein the same is shown with a hack saw blade properly supported thereby.

Figure 2 is an end elevational view of Fig. 1,

Figure 3 is a side elevational view showing parts of the frame broken away, and 40 further showing one means of adapting the handle for supporting a file,

Figure 4 is a similar view to Fig. 3 and shows a second form of an attachment for 45 properly supporting a file,

Figure 5 is a fragmentary sectional view taken on line V—V of Fig. 1,

Figure 6 is a detail view of one of the 50 clamping members employed by the invention,

Figure 7 is a detail view of one of the file supporting elements, and

Figure 8 is a sectional view taken upon 55 line VIII—VIII of Fig. 1.

Referring to the accompanying drawing and particularly to Figs. 1 and 2 there is

shown an adjustable tool handle frame embodying a rear section 1 and a front section 2. The rear section 1 consists of a longitudinal channel arm 3 having formed 60 integrally therewith and extending at right angles thereto, a depending leg 4 that is provided with a laterally extending foot member 5 at its lower end. This foot member 5 is longitudinally slotted for a portion 65 of its length, as at 6, while the unchanneled portion 7 is provided with a longitudinally extending bore 8 which is adapted for loosely receiving the threaded end of a clamping element carried by the 70 various tool engaging members. This rear section 1 is provided with a hand grip portion 9 that is similar in construction to the hand grip portion carried by the front section 2, but is somewhat differently formed 75 in shape. As Fig. 2 shows an end view of the hand grip carried by the front section and better shows the exact construction, it is believed that a detailed description of this grip, when section 2 is more fully described, will be sufficient for both.

The front section 2 is provided with a longitudinal arm 10 having a reduced end portion 11, as best shown in Fig. 1, and is further provided with a depending leg portion 12 having an enlarged lower end 13. Formed in this enlarged portion 13, adjacent its upper end, is a transverse bore 14 which is adapted for receiving one of the clamping members employed to support the 90 forward tool engaging member and is further provided with a threaded recess 15 which is adapted for receiving the screw 16 therein. Referring particularly to Fig. 2 there is shown a forward hand grip which 95 embodies a core member 17 that is formed integrally with the front section 2 and is provided with face plates 18 that are secured to the core by means of the screws 19 and are constructed from any suitable material, such as wood, bone, rubber composition, or the like.

Referring particularly to Fig. 1 and Fig. 5 there is shown a means for securely clamping the two sections 1 and 2 in their adjusted position. The reduced end portion 11 formed on the longitudinal arm 10 is provided with a number of series of transverse recesses which, in this particular showing, displays two separate series, but it is to be understood that the number may vary according to the desire of the manufacturer 105 110

without departing from the spirit of this invention. Each series embodies a central recess 19 and a pair of relatively small recesses 20 that are positioned one on either side of the central recess. One side of the channel arm 3 carried by the rear section 1 is provided with a similar series of recesses that are adapted to aline with the recesses 19 and 20 carried by the reduced end 11, 10 while the opposite side of this channel arm 3 is provided with a single recess 21 that alines with the central recess formed in the first mentioned side. The channel member 3 and reduced end 11 are adapted to be retained 15 in their adjusted position by the clamping bolt 22 that is provided with a rectangular head 23 adapted for carrying a pair of pin members 24 which are spaced laterally from the shank of the bolt. It will be clearly seen 20 in Fig. 5 that the bolt 22, when positioned within the recesses 19 and 21 and the recess alining therewith and formed in the opposite side of the channel arm 3, will properly position the pins 24 for being inserted through 25 the suitable recesses formed in one side of the channel arm 3 and engage the similar recesses 20 formed in the reduced end 11 and that the winged nut 25 will retain these members in this assembled position when 30 tightened upon the bolt 22.

The front tool supporting member is employed when the handle is used as either a support for a hack saw blade or for a file and consists of a body portion 26 that is 35 provided with a foot portion 27 at its lower end. Formed in this body portion 26 is a longitudinally extending slot 28 that terminates short of the foot portion 27 and is adapted for receiving the bolt 16 which is 40 provided with a knurled nut 29, as shown. There is further provided a clamping bolt 30 that extends through this longitudinal recess 28 and the transverse bore 14 formed in the enlarged end 13 of the depending leg 45 12. This clamping bolt 30 is shown in detail in Fig. 6 and embodies a rectangular head 31 that is provided with laterally extending lugs 32 which form pockets 33 that are adapted for engaging the side members 50 of the body portion 26. This clamping bolt 30 may be provided with a winged nut 34, as shown in Fig. 1, or a knurled nut 35, as 55 shown in Figs. 3 and 4. The foot portion 27 carried by the body portion 26 is provided with a longitudinally extending bore 36 that is adapted to receive a hack saw blade supporting post 37 that is provided with a laterally extending pin 38 carried by the outer end and adapted to engage the usual 60 aperture formed in the end of a hack saw blade. The foot portion 27 is provided with a transverse slot 39 that is adapted to receive a pin 40 carried by the post 37 and is provided for allowing angular adjustment of a hack saw carried by the frame.

The rear support for the hack saw blade 41 comprises a body portion 42 that is adapted to be positioned within the longitudinally extending slot 6 formed in the foot portion 5, and is further provided with a longitudinally extending threaded post 43 that is positioned within the bore 8, as shown, and is adapted for receiving a knurled thumb nut 44 for securely clamping the supporting member in place. The body portion 42 is 70 further provided with a depending leg 45 having a transverse bore 46 that is adapted to receive the threaded post 47 which is provided with a laterally extending pin 48 for engaging the usual aperture formed in 75 the end of a hack saw blade and is further provided with a winged nut 49 which is employed to place tension upon the hack saw blade 41 for retaining it in its proper position. 80

Referring particularly to Figs. 3, 4 and 7, there is shown a clamping means for securing various forms of files to the handle. This clamping element embodies a pair of side plates 50 and 51 which are adjustably 90 engaged by the thumb screws 52 as best shown in Fig. 7. The clamping plate 50 is provided with a laterally extending arm 53 that is adapted to be positioned within the longitudinally extending slot 6 formed in 95 the foot 5 and is further provided with a threaded post 54 that is adapted to be positioned within the bore 8 carried by the said foot. This threaded post is provided with a knurled nut 55 which will securely hold 100 the clamping element in place. The clamping plates 50 and 51 are provided upon their mating faces with a recess 56 and lug 57 respectively which coacts with the thumb screws 52 for preventing relative movement 105 between the two plates. There is also provided a substantially rectangular recess formed by mating channels 58 and 59 which are adapted to suitably clamp the usual rectangular shank formed on certain types 110 of files. There is further provided a substantially square recess 60 that is formed from channels cut in the mating faces of the two clamping plates and is adapted for securing a square sleeve 61, as best shown in 115 Fig. 4, which is provided with a longitudinally extending bore 62 adapted for receiving the shank 63 formed on the file 64. This sleeve is further provided with thumb screws 65 for securely clamping the said file 120 shank in place.

It is believed from the above detailed description of the various elements assembled to provide this tool handle that no further explanation is necessary, and that the operation will be apparent. 125

It is to be understood that the form of this invention herewith shown and described is to be taken as the preferred example of the same, and that various changes in the 130

shape, size, and arrangement of parts may be resorted to without departing from the spirit of the invention or the scope of the subjoined claim.

Having thus described the invention, I claim:—

- A tool handle comprising a pair of members adjustable longitudinally with respect to each other and means for securing said members in adjusted position, one of said members being provided with a vertical body portion terminating at its lower end in a rearwardly extending foot having a channel recess at its forward end and a wall at its rear end forming the rear end of the channel recess and provided with a bore, an angled tool support having a horizontal portion fitting said recess and provided with a threaded shank extending
- through said bore, a nut on said shank, said tool support further having a vertical portion provided with means for adjustably securing a tool thereto, the second member having a vertical body portion, a tool support mounted against the forward face of the lower end of the last mentioned vertical body portion and slotted from front to back, the slot extending from a point adjacent the upper end of the support to a point adjacent its lower end, a T-bolt extending through the upper end of the slot and the vertical body portion and having a nut thereon, a stud bolt screwed in said body portion and projecting through said slot, and a nut on said stud bolt.

In testimony whereof I affix my signature.

MICHAEL FALOS.
